UNITED STATES PATENT OFFICE.

ADOLPH SIEGEL, OF NEW YORK, N. Y.

DESIGN FOR A COLLAR.

41,483.

Specification for Design. Patented June 13, 1911.

Application filed March 18, 1911. Serial No. 615,443. Term of patent 3½ years.

To all whom it may concern:

Be it known that I, ADOLPH SIEGEL, a citizen of the United States, residing at New York, in the county of New York and State of New York, have invented a new, original, and ornamental Design for Collars, of which the following is a specification, reference being had to the accompanying drawing, forming part thereof.

The figure is a plan view of the collar.

I claim:—

The ornamental design for a collar, as shown.

ADOLPH SIEGEL.

Witnesses.

NATHAN GOLDENBERG,
VICTOR SIEGEL.
